DEVICE FOR LIFTING COOKING UTENSILS
OR THE LIKE

Edgar H. Luck, Hillsdale, Ontario, Canada

Application February 10, 1941, Serial No. 378,135
In Canada March 26, 1940

4 Claims. (Cl. 294—28)

This invention relates to devices for lifting pie plates and other cooking vessels or utensils or other similar articles and the object of the present invention is to provide a device of this character which is simple in construction and operation, may be cheaply manufactured and yet be durable and efficient.

The constructions are hereinafter more fully described and are, by way of example, illustrated in the accompanying drawing in which

Fig. 1 is a plan view of the device showing it in its inoperative position;

Fig. 2 a side elevation thereof; and

Fig. 3 a view similar to Fig. 2 showing the device in its operative position in engagement with a pie plate.

The device comprises a frame 1 which may be made from a single length of wire. The frame includes a body portion having an end 2, sides 3, lateral extensions 4, downwardly extending jaw portions 5, rearwardly directed jaws 6 and a hand grip 7. The latter extends rearwardly from the said end 2 and may be provided with an insert 8 made of wood or other suitable material having grooves 8a in its sides to receive the wire of the hand grip 7. Preferably the sides 3 of the frame 1 converge from the end 2 towards the forward end of the frame and are secured together by a plate 9 having lugs 10 for embracing the sides 3. The body portion is thus substantially triangularly shaped. The plate also has lugs 11 for embracing the extensions 4 which extend laterally from the forward ends of the sides 3. The jaw portions 5 extend downwardly from the lateral extensions and the jaws 6 are directed rearwardly from the extremities of the jaw portions.

On the end 2 is pivoted a carrier 12 which also may be made from a single length of wire. The carrier comprises a transverse rod 13 having jaw portions 14 which are curved at 15 intermediate their ends to partially embrace the end 2 of the frame 1. A transverse bar 16, which also may be made of a single length of wire, is looped at 17 around each jaw portion 14 and is curved at 18 in a direction opposite to the adjacent curvature 15 to co-operate with the latter to form a pivotal connection on the end 2. The free ends of the bar 16 are looped at 19 around the jaw portions 14, or are otherwise secured thereto, above the curvatures 18 whereby the latter are firmly positioned relative to the adjacent curvatures 15 of the jaw portions 14 to prevent longitudinal displacement of said portions and yet permit said portions to swing freely on the end 2.

The jaw portions 14 on the carrier, when the latter is in its operative position, are directed downwardly and have forwardly directed jaws 20 at their extremities.

5 The transverse rod 13 of the carrier 12 may be engaged by the operator's thumb to swing the pivoted jaws 20 towards the rigid jaws 6 so that the jaws will engage a cooking utensil to enable it to be lifted by the device. A spring 21 suitably engaging or connected with the frame 1 and the pivoted carrier 12 tends to swing the pivoted jaws 20 away from the rigid jaws 6 to an inoperative position. The spring 21 may be a coil disposed on the frame end 2 with one end of the spring looped around the upper end of the adjacent pivoted jaw portion 14 and the other end looped around the hand grip 7. The transverse bar 16 extends from one jaw portion 14 to the other to prevent the pivoted jaws from spreading 10 apart and it passes beneath the hand grip 7 so that it engages the underside thereof to limit the swinging movement of the carrier by the spring 21. The transverse rod 13 is thus positioned for ready engagement by the operator when it is desired to swing the pivoted jaws into their operative position.

From the above description it is obvious that by positioning the rigid jaws 6 under the usual rim 22 of a pie plate 23 (or other cooking utensil 30 such as a pudding dish etc.) and applying a slight pressure to the transverse rod 13, the pivoted jaws 20 will be swung into engagement with the utensil beneath the rim at the side thereof remote from that engaged by the rigid jaws. The operator may then readily lift the plate or dish into or out of a heated oven in a minimum period of time without danger of being burnt and without any appreciable loss of heat from the oven. It will be noted that the jaws 6 and 20 are well 40 spaced from the frame 1 so that the latter will not contact deep icings on pies etc. The jaw portions 5, 14 are directed forwardly and rearwardly respectively and the jaws 6, 20 are directed upwardly to facilitate the engagement thereof 45 with rims of pie plates having inturned edges.

What I claim as my invention is:

1. A device of the character described comprising a wire frame having a transverse end portion; a hand grip carried by said end portion; a plurality of jaw portions rigidly carried by said frame, the jaw portions being remote from the hand grip, extending downwardly and forwardly from the frame, and having rearwardly directed jaws at their extremities for engaging the underside of a rim of a cooking

utensil; a wire carrier pivoted on said frame comprising a transverse rod having downwardly and rearwardly extending jaw portions on the opposite ends thereof, and forwardly directed jaws on the extremities of the last mentioned jaw portions for engaging the underside of said rim at points spaced circumferentially from one another and from the first mentioned jaws; a transverse bar positioned beneath the hand grip and connected with the last mentioned jaw portions; and means tending to rock the carrier to swing its jaw portions away from the first mentioned jaw portions, the transverse bar being adapted to engage the underside of the hand grip to limit the movement imparted to the carrier by the said rocking means, the transverse rod being positioned above the pivot of the carrier and adjacent the hand grip for engagement by the thumb of an operator's hand while holding the hand grip thereby so that the jaw portions on the carrier may be rocked to their operative position.

2. A device of the character described comprising a wire frame having an end portion; a hand grip carried by said end portion; downwardly extending jaw portions rigidly carried by said frame at points remote from the hand grip for engaging the underside of a rim of a cooking utensil; a wire carrier provided with downwardly extending jaw portions for engaging the underside of said rim at points spaced circumferentially from one another and from the first mentioned jaw portions, the jaw portions on the carrier being curved intermediate their ends to partially embrace the said end portion of the frame; and wire means carried by said jaw portions on the carrier for completing the said partial embracements of the said end portion to form a pivotal connection for the carrier thereon.

3. A device of the character described comprising a frame having a hand grip; a plurality of jaw portions rigidly carried by said frame, the jaw portions being remote from the hand grip, extending downwardly and forwardly from the frame, and having rearwardly directed jaws at their extremities for engaging the underside of a rim of a cooking utensil; and a carrier

5 pivoted on said frame comprising a transverse rod having downwardly and rearwardly extending jaw portions on the opposite ends thereof, and forwardly directed jaws on the extremities 10 of the last mentioned jaw portions for engaging the underside of said rim at points spaced circumferentially from one another and from the first mentioned jaws, the transverse rod being positioned above the frame and adjacent 15 the hand grip for engagement by the thumb of an operator's hand while holding the hand grip thereby, the frame having an end portion, the jaw portions on the carrier being curved intermediate their jaws and the transverse rod 20 to partially embrace the said end portion of the frame; and wire means carried by said jaw portions on the carrier for completing the said partial embracements of the said end portion to form a pivotal connection for the carrier thereon.

4. A device of the character described comprising a wire body portion having an end, a hand grip extending rearwardly from said end, and jaw portions extending downwardly 25 from said body portion remote from said end and hand grip; a wire carrier including a transverse rod positioned adjacent to and above the hand grip and having jaw portions extending downwardly therefrom at opposite ends thereof, the last mentioned jaw portions being curved 30 intermediate their ends to partially embrace the said end of the body portion; a transverse bar positioned beneath the hand grip, being connected with the last mentioned jaw portions 35 and being curved to partially embrace the said end of the body portion for co-operation with the curved part of the jaw portions to form a pivotal connection on the said end; and means tending to rock the carrier to swing its jaw portions away from the first mentioned jaw portions, the transverse bar being adapted to engage the underside of the hand grip to limit the movement imparted to the carrier by the said rocking means, the transverse rod serving 40 as a thumb piece for rocking the jaw portions on the carrier to their operative position.
